UNITED STATES PATENT OFFICE.

ALBERT E. JOHNSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEATING APPARATUS.

Application filed October 12, 1920. Serial No. 416,501.

To all whom it may concern:

Be it known that I, ALBERT E. JOHNSON, a citizen of the United States, residing at Beverly, in the county of Essex and State of Massachusetts, have invented certain new and useful Improvements in Heating Apparatus; and I do hereby declare the following to be a full, clear, and exact description of the invention, such as will enable others skilled in the art to which it appertains to make and use the same.

This invention relates to heating apparatus, and it has special reference to such apparatus as is adapted to heat or condition coated canvas or similar reenforcing fabric employed in the manufacture of reenforced insoles.

In the manufacture of Economy, Gem and like insoles, the reenforcing fabric employed is customarily coated on one side with a composition which, at ordinary temperatures, is non-adhesive, but which is rendered adhesive upon being subjected to a predetermined degree of heat.

In heating apparatus heretofore employed for conditioning coated fabric of this general character, the coated fabric, either in the form of a strip or of died-out pieces, has been placed upon or moved slowly over a suitable heating device with its coated surface uppermost. In such apparatus, whatever its particular type, the heating device is located directly below the fabric and imparts heat to the coating through the medium of the fabric itself. Moreover, when the coated fabric is either drawn in a strip or carried in pieces by a conveyer at a uniform rate over the heating device, the operator must keep pace with the movement of the fabric and is allowed no latitude in flexibility and speed of assembly of the fabric with the usual insole blanks, or in the exercise of skill or judgment in the assembling operation.

The general object of the present invention is to improve the construction, efficiency and flexibility of operation of heating apparatus of the above indicated class and to produce results of a uniformly superior character.

More specifically, an object of the invention is to provide a heating apparatus in which heat is applied directly to the upper coated surface of the fabric by means of a heating device located immediately above

the fabric and which preferably moves progressively over the fabric at a slow rate, during which the coated surface is heated to the desired temperature.

Another object of the invention is to provide a heating apparatus in which the material or coated fabric to be heated is conditioned primarily by the direct application of considerable heat for a short period to the coated surface thereof and, after being brought up to the desired temperature, is maintained in proper working temper or condition by imparting a relatively small amount of heat to the fabric until the operator is ready to perform the assembling operation.

A further object of the invention is to provide an apparatus of the character indicated which is electrically heated and which is so constructed and arranged as to consume a minimum amount of electrical energy, while heating the coated fabric to the desired temperature and maintaining it in proper condition until the operator is ready to perform the assembling operation, and also while permitting the operator to control the apparatus in accordance with his judgment and skill, as well as with respect to existing operating conditions.

To these ends, the present invention embodies several important features of construction, one of which contemplates a heating device disposed above and in proximity to the material or coated fabric and which is movable progressively over it throughout the length of the machine to impart heat rapidly and directly to the upper surface thereof as it passes along. Suitable mechanism, conveniently embodying a feed-screw, is employed to move or feed the movable heating device, and a reversing clutch driving mechanism is preferably employed to arrest the feed movement and to cause the feed-screw to return the heating device to its initial position.

Another feature of the invention resides in the provision of a heated support or table on which the material or coated fabric to be heated is placed and which, to a limited extent and in conjunction with the heating device disposed above and in proximity to the support, serves to raise the material or coated fabric to the desired temperature and subsequently to maintain the material or coated fabric in proper working temper.

or condition after the heating device has become ineffective.

A further feature of the invention embraces the use of electric heater units associated with the support or table and the movable heating device, and automatic control devices for governing the supply of energy thereto so that energy is supplied to the heater units during the movement or travel of the movable heating device in one direction, and is interrupted at the limit of travel and maintained interrupted during the reverse return movement of the movable heating device, the support or table preferably having sufficient heat storage capacity to maintain the fabric in proper working condition for a considerable period while the supply of electric energy is cut off.

These and other objects of the invention and the means by which they are attained will be clearly understood from the following description of the preferred embodiment of the invention illustrated in the accompanying drawings, in which:

Figure 1 is a view in front elevation of a portion of an apparatus constructed in accordance with the invention, the upper supply table or shelf being omitted; Fig. 2 is a plan view of the apparatus shown in Fig. 1; Fig. 3 is an enlarged view in end elevation, looking at the right hand end of the apparatus; Fig. 4 is a detailed sectional view taken on the section line 4—4 of Fig. 3; Fig. 5 is a similar view taken on the section line 5—5 of Fig. 4; Fig. 6 is an enlarged view, partially in end elevation and partially in section on the section line 6—6 of Fig. 2; Fig. 7 is an enlarged sectional plan view of the reversing clutch driving mechanism; Fig. 8 is a bottom plan view of the movable heating device; Fig. 9 is a sectional view of the heating device on the section line 9—9 of Fig. 8; and Fig. 10 is a diagrammatic view of the electrical circuits of the apparatus.

While for purposes of illustration the invention is shown in the drawings and hereinafter described as embodied in a heating apparatus which is particularly adapted for heating or conditioning died-out pieces of coated reenforcing fabric such as are utilized and assembled with suitably shaped insole blanks to form what is known in the art as Economy insoles, it should be understood that this invention is not so restricted but is applicable to operating upon material of different characteristics and forms.

Referring to the drawings, the apparatus of the present invention comprises, in general, a main supporting frame upon which the various parts and mechanisms are mounted; an electrically heated support or table 20 upon which the material rests while being heated or conditioned; an elevated supply table or shelf 22 for support-

ing a supply of coated died-out pieces to be heated; a front support or assembling table 24 upon which the conditioned pieces of coated fabric and the usual insole blanks are assembled by the operator; a movable electrically heated heating device 26 that is adapted to travel lengthwise of the supporting table 20 to heat to the desired temperature the upper coated surfaces of the died-out pieces disposed thereon; a feed mechanism including a feed-screw 28 for moving or advancing the movable heating device 26 lengthwise of the apparatus; a reversing clutch driving mechanism 30 for operating the feed-screw 28 and the movable heating device 26 in opposite directions; and an electrical system comprising an electrically operated circuit interrupter 32, a terminal board 34, a plurality of electric heating units 76, and a plurality of control switches 40 and 42 by means of which the operation of the circuit interrupter 32 is automatically governed.

The supporting frame of the apparatus comprises a plurality of end pedestals 44 and 46, to the upper ends of which a bottom plate 48 is secured by means of bolts 50. To the outer ends of the bottom plate 48 a plurality of end plates 52 and 54 are fixed by means of screws 56. Joining the two front upper corners of the end plates 52 and 54 is an angle iron 58 that is fastened to the end plates by means of bolts 60. An angle iron 59 of like construction is similarly secured to the upper rear corners of said end plates. A front plate 61, preferably of asbestos, is secured to the front ends of the respective end plates 52 and 54 by means of bolts 62, to the front angle iron 58 by means of bolts 64, and to an upwardly extending rib 66 on the bottom plate 48 by means of bolts 68. A back plate 70, also preferably of asbestos, is suitably positioned in a manner similar to that of the front plate 61. Thus a substantially box-like structure having an open top is provided upon the end pedestals 44 and 46.

The electrically heated support or table 20, upon which the died-out pieces of coated fabric are placed, constitutes the top of the box structure and is removably positioned between the respective end plates 52 and 54 and angle irons 58 and 59. This supporting table 20 may conveniently be made of cast iron, or some other material of good heat storage capacity, whereby, when once heated, either electrically or by other means if desired, a sufficient amount of heat is stored and held therein to supply heat to and maintain the died-out pieces in proper heated condition or temper for a considerable period, even after the supply of heat to the table is interrupted. The supporting table 20 rests upon the heads of a plurality of set screws 72 which are adjustably threaded into

a corresponding number of laterally extending lugs 74 constituting parts of the end plates 52 and 54.

Heat is imparted to the heating support or table 20 by means of a plurality of electric heating units 76 of suitable construction which are held in place against the bottom surface of the supporting table by means of bolts 78 or other convenient devices. Thus, 5 the heating units 76 are maintained in intimate contact with the supporting table which is to be heated, and the box-like structure hereinbefore described, provides a dead air space beneath the heating units, which 10 serves as heat insulation to prevent undue radiation of heat and to confine it mainly to the supporting table itself.

The supply table or shelf 22 extends longitudinally of the machine and is supported 20 in elevated position over the rear portion thereof upon a pair of angle irons 80, which are carried at the upper ends of a pair of brackets 82, that are secured by bolts 84 to the respective end pedestals 44 and 46. This 25 supply table or shelf 22 serves to support a supply of died-out pieces of coated fabric in such position as to be readily accessible to the operator who, as the occasion requires, places them in position in a row upon the 30 heated supporting table 20 with their coated surfaces uppermost.

Extending along the full length of the apparatus is located the front or assembling table 24. This assembling table may be of 35 any suitable construction and is supported in the plane of the heated support or table 20 upon a plurality of brackets 86 that are bolted to the bottom plate 48 and which extend forwardly into proper supporting position. 40 The assembling table 24 is utilized by the operator at proper times during the operation of the apparatus in assembling the conditioned or heated pieces of coated fabric upon insole blanks which have been previously suitably formed and shaped, in accordance with well-known practice which need not be herein described.

While the heated supporting table 20 is intended to supply a certain degree of heat 50 to the row of pieces of coated fabric placed thereon, the upper coated surfaces thereof are heated to the desired temperature mainly by means of the movable heating device 26 which is moved lengthwise of the apparatus 55 in a plane parallel to, above, and in proximity to the heated supporting table 20, and which rapidly imparts heat to the pieces as it progressively passes over them in succession. The adhesive coating of the pieces is 60 thus heated or conditioned primarily by the direct application of heat from the movable heating device 26, although the heated support 20 serves also to impart some heat indirectly thereto through the medium of the 65 fabric itself. The principal function of the

heated support 20, however, is to supply sufficient heat to the died-out pieces after the movable heating device 26 has passed over them, and even after the supply of heat has been cut off, to compensate for radiation and 10 maintain the pieces in proper working temperature or condition until the operator is ready to assemble them with the insole blanks in the manner of the prior art.

The movable heating device 26 comprises 75 a narrow forwardly extending member 90 (Fig. 9) which is channel-shaped in section, being provided with downwardly projecting side members 92, to the lower ends of which are secured strips or ways 94 which 80 serve to support a plate or member 96 of insulating material on the under side of which a suitable electric heater unit 98 is mounted, the unit illustrated being made of coiled resistance wire, as shown particularly in Figs. 85 8 and 9. The plate 96 and associated heater unit 98 may be easily withdrawn along the supporting ways 94 and removed from the front end of the member 90 for purposes of repair or replacement. Normally the plate 90 95 is held in position by set-screws 100, and the front end of the heater unit is protected by a covering 102 of sheet material that is secured to the forward end of the member 90 in any convenient manner. As shown in Fig. 8, the respective ends of the heater unit 98 are connected by means of bolts 104 to a pair of bars or strips 106 of conducting material which serve also to enclose the 100 heater unit.

For the purpose of protecting the heater unit from contact with any of the pieces of coated fabric during the travel of the movable heating device 26 from one end of the apparatus to the other, a plurality of guard 105 wires 108 forming a protecting screen are secured in position beneath the heater unit. This is accomplished by clamping or gripping the respective ends of each of the guard wires 108 between pairs of clamping strips 110 and 112 that are secured by means of a series of screws 114 to the respective downwardly projecting sides 92 of the member 90. The outer edges of the clamping strips 110 are provided with a series of holes 116 115 to receive and position the ends of the guard wires 108.

In order to permit the movable heating device 26 to be adjusted vertically to properly space the heater unit 98 from the heated support or table 20, the rear end of the member 90 is provided with a rearwardly projecting vertically extending tongue 120 that is received in a slot in an upwardly projecting bracket 122, constituting part of a movable carriage 124, the member 90 being rigidly secured to the bracket 122 by means of a bolt 126. An electric switch 128 is suitably mounted upon an upwardly projecting portion 130 of the member 90, and this 130

switch is so connected in the electric circuit of the heater unit 98 associated with the movable heating device 26, that the supply of electric energy thereto may be controlled 5 at the will of the operator.

The movable heating device 26 is arranged to be actuated in either direction longitudinally of the apparatus, and to the accomplishment of this end, the movable carriage 10 124, upon which the heating device is mounted, is actuated by means of a feed-screw mechanism which embodies the feed-screw 28. This feed-screw is provided with threads 15 of great pitch extending substantially throughout the length thereof and is mounted for rotatable movement in bearings 130 and 132 adjacent its respective ends. These bearings form parts of a plurality of supporting brackets 134 and 136 20 respectively that are fixed to the respective end plates 52 and 54 of the supporting frame. In order to effect the feed movements of the carriage 124, the feed-screw 28 is provided with an internal threaded nut 25 or block 138 (Figs. 4, 5 and 6) which is received in an opening 140 in the carriage 124. The threaded block 138 and the opening 140 are substantially rectangular in form, whereby the threaded block is prevented from 30 partaking of the rotative movements of the feed-screw. A slight clearance between the threaded block 138 and the sides of the opening 140 is provided to prevent binding. With this construction, any rotative movement 35 of the feed-screw 28 causes the threaded block 138 to travel longitudinally thereof in one direction or the other, whereby the carriage 124 and movable heating device 26 are also moved. The movable heating device 26 is maintained in proper position throughout 40 its movements through the agency of a plurality of rolls 144 and 146 that cooperatively engage a guide rod 148 extending longitudinally above the feed-screw 28, in conjunction 45 with a roll 150 that engages an angle iron 152 secured to the supporting brackets 134 and 136 at its respective ends and which is additionally supported intermediate its ends by means of brackets 154 50 which are fastened to the bottom plate 48 and project rearwardly therefrom.

Inasmuch as the movable heating device 26 is to be adapted for movement in either direction longitudinally of the apparatus, it 55 is necessary to make provision for rotating the feed-screw 28 in opposite directions, and this is accomplished by means of the reversing clutch driving mechanism 30, shown particularly in Figs. 2 and 7. This mechanism 60 comprises a plurality of toothed clutch members 158, 160, 162, and 164, that are associated with the right hand end of the feed-screw 28 which projects beyond the bearing 132, the clutch members 158 and 164 65 being pinned to the feed-screw while the

clutch members 160 and 162 are loosely mounted thereon. The clutch member 160 constitutes a part of a hub portion 166 of a small grooved pulley 168, while the clutch member 162 is provided on a hub portion of 70 a relatively large pulley 170 which is provided with a circular laterally extending flange 172 forming a circular recess 174 into which projects a peripheral flange 176 forming an integral part of the pulley 168. Sufficient clearance is provided between the outer periphery of the flange 176 and the inner periphery of the flange 172 to permit the pulleys to be independently rotated. An 75 annular ring 178 is screwed to the lateral face of the flange 172 and projects inwardly to provide a loose connection between the two pulleys, whereby both pulleys may be shifted as a unit longitudinally along the feed-screw 28, as desired. This shifting of 80 the pulleys and, therefore, of the loose clutch members 160 and 162 is effected by means of a shift-lever 180 having a plurality of rolls 182 mounted on its bifurcated arms and which are disposed in a groove 184 in the 85 hub member 166 of the pulley 168. The shift-lever 180 is pivotally mounted upon a bracket 186 that is secured to the end pedestal 54, and the forward end of the shift-lever has a pivotal connection to a longitudinally disposed rod or control handle 190, 90 that extends beneath the forward edge of the assembling table 24 throughout its full length, being held in position by suitably slotted brackets 192 which are secured to 95 the respective ends thereof. The control rod or handle 190 is therefore loosely mounted for longitudinal movement in either direction in such position that it may be readily grasped and operated by the operator as 100 desired, in order to control the operation of the reversing clutch driving mechanism 105 30.

The reversing clutch driving mechanism, just described, is adapted to occupy a neutral or intermediate position in which neither of the sets of cooperating clutch members are in engagement, and two operative or driving positions, one in which the clutch members 158 and 160 become operative 110 to drive the feed-screw 28 in one direction and the other in which the clutch members 162 and 164 become operative to effect the driving of the feed-screw in the opposite direction. The pulleys 168 and 170, during 115 the operation of the machine, are continuously driven by means of belts 196 and 198 from a double pulley 200 carried on the end of a shaft 202 of a driving motor 204 which is suitably mounted at one end of the machine upon the side pedestal 46. The belt 198 is crossed so that the pulley 168 is operated in a reverse direction from the pulley 170. Thus, when the clutch members 162 and 164 are in driving engagement, the 120 125 130

large pulley 170 serves to rotate the feed-screw 28 slowly to cause the movable heating device 26 to be moved slowly over the heated support or table 20 in a direction to the left as viewed in Figs. 1 and 2, while if the clutch members 158 and 160 are thrown into engagement, the small pulley 168 functions to rapidly rotate the feed-screw 28, whereupon the movable heating device is rapidly moved or fed in a direction to the right.

With the reversing clutch driving mechanism just described, it will be understood that the operator may have full control of the movements of the movable heating device 26, and by properly actuating the shift-lever 180, may operate the clutch mechanism in such a manner as to effect feed movements of the heating device in either direction or may arrest its movement at will. However, to relieve the operator of the necessity of constant attention, automatic means is provided for arresting the movements of the heating device 26 when it reaches its limit of travel in either direction. This is accomplished by means of a longitudinally disposed control rod 210 which is mounted at its respective ends for sliding movement in suitable apertures in the brackets 134 and 136. The right hand end of the control rod 210 has a pivotal connection 212 to the shift-lever 180 and adjacent each end of the control rod is located an adjustable collar or limit stop 214. The control rod 210 is actuated by means of a forwardly extending lug 216 (Fig. 6) having a slot 218 to receive said rod. This slotted lug 216 is provided upon the carriage 124 and the limit stops 214 are so adjusted in position upon the rod as to be engaged by the slotted lug 216 when the carriage and therefore the movable heating device 26 have reached their limit of travel, or, at least, that point in their travel at which it is desired to arrest their further movement. For instance, assuming the reversing clutch driving mechanism to occupy the position shown in Fig. 2, the carriage 124 and heating device 26 are moved slowly to the left throughout the length of the machine until the slotted lug 216 engages the limit stop 214 at the left hand end of the control rod 210. Thereupon, the control rod is actuated to the left to throw the clutch mechanism into neutral or inoperative position, thereby disconnecting the feed-screw 28 from the source of power and bringing the movable heating device 26 to rest. Obviously a similar operation takes place at the opposite limit of travel of the movable heating device 26. Having thus automatically arrested the feed movement of the heating device 26, said device remains at rest at whatever end of the apparatus it happens to occupy until the operator throws the reverse clutch driving mechanism from its neutral position into such position as to

reverse the direction of feed of the heating device. This operation is readily effected by the operator in whatever position he happens to be standing along the front of the assembling table 24, inasmuch as the operating rod or handle 190, to which the shift lever 180 is attached, is readily accessible from any position.

While it is preferred to arrest the movement of the heating device 26 at the respective ends of the apparatus in the manner just described, it is possible, if found for any reason desirable, to so adjust the positions of the limit stops 214, that instead of shifting the reverse clutch driving mechanism to its neutral position, the shifting movement may be rendered sufficiently great as to throw the clutch mechanism past its neutral point and into reverse driving relation. Thus, a reversal of the direction of feed of the movable heating device may be automatically accomplished.

Having set forth the mechanical construction and operation of the preferred embodiment of the invention illustrated, the electrical system and its operation will be described. For this purpose reference will be made largely to Fig. 10, which shows diagrammatically the electrical system, it being considered unnecessary to a comprehensive understanding of the invention to describe the detailed wiring and the structure and operation of the well-known auxiliary electrical devices employed.

The electrical system comprises, in general, a main switch 220, the electro-magnetic circuit interrupter 32, the terminal board 34, the stationary heater units 76, the movable heater unit 98, a switch 128 in the movable heater circuit, automatic control switches 40 and 42, and the necessary main circuit and control circuit connections.

The main switch 220 and the circuit interrupter 32 are conveniently mounted on the end pedestal 44 and may be of any suitable construction. The circuit interrupter 32 is of the double-pole type, being provided with two sets of stationary contact members 222 and cooperating movable contact members 224. The movable contact members 224 of the circuit interrupter are normally biased to their open or inoperative positions by means of a spring 226 and are actuated into their closed positions in engagement with the stationary contact members 222 by means of an electrically energized closing coil 225, which coil also serves to hold the circuit interrupter closed in operative position so long as the energization of the coil is continued.

The terminal board 34 may also be of any suitable construction and is preferably mounted beneath the bottom plate 48 and insulated therefrom. Briefly, the terminal board 34 is provided with two main ter-

minals 228, one of which is connected through plug-and-socket switches 230 (Figs. 1 and 10) to one end of the stationary heater units 76, while the other terminal is connected through plug-and-socket switches 232 to the other ends of said heater units. The heater units 76 are thus connected in parallel or multiple relation. The use of the plug-and-socket switches 230 and 232, while not essential, is rendered desirable in order to permit of the ready disconnection of the heating units 76 when the removable supporting table 20, to which they are attached, is for any reason removed. The main terminals 228 of the terminal board 34 are also connected to one end of the double-conductor flexible cable 236, the other end of which is connected to the respective ends of the movable heater unit 98. This unit is thus connected in multiple with the stationary heater units 76. The switch 128, which is mounted upon the movable heating device, is connected in the circuit of the heater unit 98 in order to permit the operator to control, at will, the supply of energy thereto.

The control switches 40 and 42 are utilized in conjunction to automatically control the supply of energy to the heating units 76 and 98 and are so constructed and arranged in the circuit of the closing and holding coil 225 of the circuit interrupter 32 as to energize the coil 225 to cause the interrupter to close to supply energy to the heater units when the movable heating device 26 occupies its starting position at the right hand end of the apparatus, and moreover, to maintain the interrupter closed throughout the slow travel of the heating device across the apparatus until it reaches its limit of travel at the left hand end thereof. During this travel of the movable heating device 26, the heater units 76 and 98 function to impart heat to the died-out pieces of coated fabric which the operator has placed upon the supporting table 20. When the movement of the heating device 26 is arrested at the left hand end of the apparatus, the control switches 40 and 42 serve to deenergize the closing and holding coil 225 to permit the spring 226 to open the circuit interrupter 32 to cause the interruption of the supply of energy to the heater units and, moreover, to maintain this interruption during the return movement of the movable heating device 26 to its initial position, whereupon the closing and holding coil 225 is again energized through the switches 40 and 42 and the circuit interrupter 32 is closed to reestablish the supply of energy to the heater units.

The control switch 40 is conveniently mounted upon the bracket 134 at the left hand end of the apparatus and comprises a stationary contact terminal 240 which is normally engaged by the free end of a movable

spring member 242. The control switch 42 is located on the bracket 136 at the other end of the apparatus and similarly comprises a stationary contact terminal 246 and a movable spring member 248. The spring member 248, however, is so arranged as normally to be held out of engagement with its contact terminal 246. The operation of these control switches 40 and 42 is automatically effected at the respective limits of travel of the movable heating device 26 by means of a switch actuating plate 250 (Fig. 5) of insulating material which is secured by means of screws 252 to the lower surface of the movable carriage 124. The forward side of the actuating plate 250 is slotted to avoid the mounting of the roll 150 and is provided with projecting lugs 254 having oppositely inclined surfaces that are respectively adapted to engage the spring members 242 and 248 of the switches 40 and 42. This engagement, of course, is effected only when the movable carriage 124 substantially reaches its respective limits of travel in either direction. The spring member 248 is actuated into contacting engagement with its stationary terminal 246 when the movable heating device 26 is in its initial starting position, and the spring member 242 is actuated to disengage its contact terminal 240 when the heating device reaches its extreme left hand limit of travel.

The electric circuit connections and operation will be best understood from the following description of the general operation of the machine. Assuming the connections to be as illustrated in Fig. 10, the driving motor 204 to be in operation and the movable heating device 26 to occupy its starting position as shown in Figs 1 and 2, in which position the normally open control switch 42 is held closed by the engagement of one of the lugs 254 of the switch actuating plate 250, the operation is as follows. The main switch 220 and the auxiliary switch 128 are first closed by the operator. Thereupon, a control circuit is established from one side A of the source of energy which includes one pole 258 of the main switch 220, conductor 260, conductor 262, closing coil 225, conductor 264, contact members of the control switch 40, conductor 266, contact members of the control switch 42, conductor 268, conductor 270, and thence through the other pole 272 of the main switch 220 to the other side B of the source of energy. The closing and holding coil 225 of the circuit interrupter 32 is thus energized and serves in a well-known manner to electro-magnetically actuate and close the circuit interrupter 32. Energy is then supplied to the heater units 76 and 98 through a circuit which includes the conductor 260, cooperating contact members 222 and 224 of one pole of the circuit in-

terrupter, and conductor 274 to one terminal 228 of the terminal board 34 where the circuit divides to connect the two stationary heater units 76 through the plug-and-socket switches 230 and 232 in multiple and to connect the movable heater unit 98 through the flexible cord 236 and switch 128 in multiple to the units 76, the branch circuits uniting at the other terminal 228 of the terminal board 34 and the circuit continuing through the conductor 276, cooperating contact members 222 and 224 of the other pole of the interrupter 32, and thence to conductor 270. Thus, heat is supplied to the various heater units of the apparatus, the heat delivered by the stationary heater units 76 serving to raise the temperature of the supporting table 20, which, having a considerable heat storage capacity, as already explained, stores or accumulates heat therein for future use, as will be hereinafter set forth. The movable heating device 26, as will be noted in Figs. 1 and 2, is at this time located in a position beyond the supporting table 20 and therefore is prevented from imparting heat to the coated fabric which already may have been placed upon the table by the operator.

In starting the apparatus into operation initially, the operator preferably allows heat to be stored or accumulated in the supporting plate 20 for a period before starting the feed movement of the movable heating device 26. During this period, heat is gradually imparted through the table 20 to the fabric side of the died-out pieces lying thereon. When sufficient heat has been stored in the table 20, the operator, by means of the shift rod or handle 190, throws the reversing clutch driving mechanism 30 into the position shown in Figs. 1 and 2, thereupon connecting the feed-screw 28 to the driving motor 204, after which the movable heating device 26 is progressively fed at a slow rate lengthwise of the machine and in proximity to the coated upper surfaces of the died-out pieces lying on the table 20. The coating of each piece is heated to the desired temperature as the heating device moves over it, the heated supporting table 20 also serving, to a limited extent, in conjunction therewith to raise the temperature to the desired amount. As soon as the movable carriage 124 leaves its initial starting position, the switch actuator 250 disengages the spring member 248 of the control switch 42, thereby permitting it to disengage its stationary contact member 246, thus opening the control circuit between the conductors 266 and 268. However, the closing and holding coil 225 is still energized through the conductor 280, one end of which is connected to one of the contact members of the control switch 40 and the other end is connected to the con-

ductor 276, which is now energized by reason of the previous closure of the circuit interrupter 32. The circuit interrupter 32 therefore, is held closed throughout the travel of the movable heating device 26 toward the left hand end of the apparatus.

As soon as the heating device passes over one of the died-out pieces of coated fabric, during which the temperature of the coating is raised to the proper amount, the operator may remove this piece from the supporting table 20 and assemble it with a suitable insole blank upon the assembling table 24 in the usual manner. The operator may thus assemble the died-out pieces as fast as they are heated, and during the continued movement of the heating device, may also replace the pieces removed with new pieces taken from the supply table.

This operation continues until the movable heating device 26 has reached its left hand limit of travel, at which time, the lug 216 engages the collar 214 at the left hand end of the control rod 210 and shifts the reversing clutch driving mechanism into neutral position to arrest further feeding movements of the movable heating device 26. Concurrently therewith, the actuating plate 250 engages the spring contact member 242 of the control switch 40, thereby disengaging this member from its stationary contact terminal 240 and interrupting the energizing circuit of the closing and holding coil 225 of the circuit interrupter 32. The spring 226 then functions to open the circuit interrupter to interrupt the supply of energy to the heater units 76 and 98. However, by reason of the heat storage capacity of the supporting table 20, sufficient heat has accumulated therein to maintain the pieces of coated fabric in proper working condition or temper after the supply of heating energy has been discontinued. The operator may then continue to assemble the heated died-out pieces, or he may, by means of the control rod or handle 190, shift the reversing clutch driving mechanism to its opposite driving position to reverse the direction of movement of the heating device 26 and cause it to be rapidly returned to its initial position. During this return movement the assembly of pieces of coated fabric with the insole blanks may be continued, or the operator may utilize a part or the whole of the return period for placing new coated pieces upon the supporting table 20.

As soon as the movable heating device 26 is restored to its initial position, the slotted lug 216 engages the collar 214 on the right hand end of the control rod 210, thereby automatically shifting the reversing clutch driving mechanism to its neutral position and arresting further feeding movements of the heating device 26. At this time the actuating plate 250 also engages the spring

8
 contact member 248 of the control switch 42 and moves it into contacting engagement with its stationary terminal 246. Thereupon, the energizing circuit of the closing 5 and holding coil 225 of the circuit interrupter 32 is again completed and the circuit interrupter 32 is again closed to deliver energy to the heating units 76 and 98 in the manner already described. The movable heating device 26, however, remains in its initial starting position until such time as the operator again throws the reversing clutch driving mechanism to cause said device to be again moved across the supporting 10 table 20 to heat the pieces of coated fabric disposed thereon. This cycle of operations is continued as long as found necessary or desirable.

From a foregoing description, it will be 20 understood that although the apparatus is semi-automatic in its operation, the operator may have substantially full control thereof and may govern the operation of the machine in a large measure in accordance with 25 his skill and judgment and with any peculiarities or difficulties in operation that may be encountered. Moreover, the supply of energy to the apparatus is intermittent, and therefore the consumption of energy is relatively low. Furthermore, considerable latitude in the assembling operation is permitted the operator by reason of the fact that when the pieces of coated fabric are once brought to the desired temperature and 30 temper, they are maintained in such condition by the supporting table 20 of heat storage capacity until the operator is ready to utilize them in the assembling operations. The operator is thus able to adapt his work 40 to the exigencies of operating conditions without sacrifice in the quality of the product that might otherwise result if the coated pieces were not maintained in the proper working temper until ready for assembly. 45 Injury to the died-out pieces of coated fabric due to a temporary absence of the operator is prevented by reason of the fact that the supply of energy to the heating units is automatically interrupted at the end of 50 travel of the movable heating device 26 toward the left of the apparatus, and, moreover, inasmuch as the starting position of said device, at which energy is supplied thereto, is beyond the supporting table 20, 55 where it is impossible to impart heat to the coated pieces from said device.

Although the invention has been shown and described as embodying more or less specific details of construction, arrangement 60 and location of parts, and mode of operation, it will be understood that many modifications may be made therein without departing from the spirit and scope of the invention. Therefore, only such limitations

should be imposed as are indicated in the 65 appended claims.

Having set forth the construction and operation of the preferred embodiment of the invention, that which is claimed as new is:

1. Apparatus for conditioning coated fabric having, in combination, a flat, stationary table upon which the fabric to be heated is placed, and a movable heating device disposed above and in proximity to said table 75 for heating the fabric to a predetermined temperature as it moves past it.

2. Apparatus for conditioning coated fabric having, in combination, a flat, stationary horizontal table for the fabric to be heated, and a horizontally movable heating device disposed above and in proximity thereto and 80 movable over said table to impart heat directly to the coating.

3. Apparatus for conditioning coated fabric having, in combination, a stationary elongated table for the fabric to be heated, a relatively narrow heating device disposed above and in proximity thereto, and power means for moving said heating device in opposite directions lengthwise of said support 90 and over said fabric.

4. A machine for conditioning coated fabric having, in combination, a flat, stationary table upon which the fabric is laid with the 95 coated surface thereof uppermost, a heating device disposed above and in proximity to the fabric upon said table, and means for moving said heating device slowly over the fabric in a plane parallel to said table to impart heat directly to the coated surface of the fabric.

5. Heating apparatus having, in combination, a heated support for material to be heated, and a heating device disposed in 105 proximity thereto and movable relatively thereto parallel to said support, for applying heat directly to both sides of the material.

6. Heating apparatus having, in combination, a support for material to be heated, means disposed in proximity to said support and movable thereover for heating the material thereon, means for discontinuing the supply of heat thereto automatically, and 110 means for heating the support to maintain the material in heated condition after said first heating means has become ineffective.

7. Heating apparatus having, in combination, a support for material to be heated, movable heating means disposed in proximity to said support and out of contact with said material but adapted to travel over said support and heat the material as it passes, and means for heating said support to maintain the material in heated condition after the movable heating means passes over it.

8. Heating apparatus having, in combina-

- tion, a support for material to be heated, a heating device disposed in proximity to said support and movable thereover, means for supplying heat to said support and said device and means for discontinuing the supply of heat thereto automatically at a predetermined point in said movement, said support having sufficient heat storage capacity to maintain the material in full heated condition for a period after the supply of heat has been discontinued.
9. Heating apparatus having, in combination, a support for material to be heated, a heating device disposed in proximity to said support and adapted to impart the main body of heat to said material, means for supplying heat to said support and said heating device and automatic means for discontinuing the supply of heat thereto, said support being adapted to assist in heating the material and having sufficient heat storage capacity to maintain the material in full heated condition for a period after the supply of heat has been discontinued.
10. Heating apparatus having, in combination, a support for material to be heated, a movable heating device disposed in proximity thereto and adapted to travel over said support and heat the material as it passes, and means for supplying heat to said support and said heating device, said heated support serving to maintain the material in full heated condition after the movable heating device passes and having sufficient heat storage capacity to maintain the full heated condition of the material for a period after the supply of heat has been discontinued.
11. Heating apparatus having, in combination, an electrically heated support of heat storage capacity upon which the material to be heated is placed, a movable electric heating device disposed in proximity to said support for heating the material to the desired temperature as it moves past it, and means for interrupting the supply of electric energy to said support and said heating device, leaving the support of heat storage capacity to maintain the heated material in heated condition after the supply of electric energy is interrupted.
12. Heating apparatus having, in combination, an electrically heated support of heat storage capacity upon which the material to be heated is placed, a movable electric heating device disposed in proximity to said support, means for moving said heating device lengthwise of said support to heat the material as it moves past it, and means for interrupting the supply of electrical energy at a predetermined point in the travel of said movable heating device, leaving the support of heat storage capacity to maintain the material in heated condition after the supply of electrical energy is interrupted.
13. Heating apparatus having, in combination, a stationary support for the material to be heated, a movable heating device disposed in proximity to said support, means for moving said heating device in one direction along the support and material to heat the material, and automatic means for arresting the movement of said heating device at a predetermined point in its movements.
14. Heating apparatus having, in combination, an elongated support for the material to be heated, a relatively narrow heating device disposed in proximity thereto, power means including a rotary member for moving said heating device in opposite directions lengthwise of said elongated support, and means for reversing the direction of movement of said member.
15. Heating apparatus having, in combination, an elongated support for the material to be heated, an electrical heating device disposed in proximity thereto, power means including a reversing clutch driving mechanism for moving said heating device lengthwise of the support in opposite directions, and means for actuating said mechanism to cause the movement of said heating device to be reversed in direction.
16. Heating apparatus having, in combination, an elongated support for the material to be heated, a relatively narrow heating device disposed in proximity thereto, power means for moving said heating device slowly along said elongated support in one direction and automatically arresting its movement, and means for reversing the movement thereof and moving said heating device rapidly in the opposite direction.
17. Heating apparatus having, in combination, a support for the material to be heated, a movable heating device disposed in proximity to said support, means for moving said heating device in one direction along the support to heat the material disposed thereon, and automatic means for arresting the movement of said heating device at a predetermined point in its movement and for interrupting the supply of heat to said heating device.
18. Heating apparatus having, in combination, a support for the material to be heated, a movable heating device disposed in proximity to said support, means for moving said heating device in one direction along the support to heat the material thereon, automatic means for arresting the movement of said heating device at a predetermined point in its movement and for interrupting the supply of heat to said heating device, and means for moving said heating device in the opposite direction while maintaining the interruption of the supply of heat thereto.
19. Heating apparatus having, in combination,

- bination, a support for the material to be heated, a movable heating device disposed in proximity to said support, means for moving said heating device in one direction along the support to heat the material thereon, automatic means for arresting the movement of said heating device at a predetermined point in its movement and for interrupting the supply of heat to said heating device, means for moving said heating device in the opposite direction while maintaining the interruption of the supply of heat thereto, and means for arresting the movement of said heating device in said opposite direction and restoring the supply of heat thereto. 5 vices in a plane parallel to the other heating device. 65
25. Apparatus for conditioning coated fabric having, in combination, a flat work table for fabric to be heated, an electrically heating device disposed above and in proximity to said table, and means for effecting relative movements of said heating device and the fabric on said table in a plane parallel to said table. 70
26. Heating apparatus having, in combination, an elongated electrically heated support for material to be heated, a relatively narrow electrically heated device disposed above and in proximity to said support and movable in a plane parallel to said support for heating the upper surface of the material. 75
27. Heating apparatus having, in combination, an electrically heated support for material to be heated, and an electrically heated device disposed above and in proximity to said support and movable in a plane parallel to said support to heat the material on said support as it moves over it. 80
28. Heating apparatus having, in combination, a support for material to be heated, an electric heater secured to the underside thereof for applying heat thereto, a movable carriage, and an exposed electrical heater mounted thereon in proximity to said support. 85
29. Heating apparatus having, in combination, a support for material to be heated, a movable device disposed in proximity to said support, means for electrically heating said device, and means for arresting the movement of said movable electrically heated device and for interrupting the supply of electrical energy to said heating means. 90
30. Heating apparatus having, in combination, a support for the material to be heated, a movable device disposed in proximity to said support, means for electrically heating said device, means for causing said electrically heated movable device to traverse back and forth longitudinally of said support, and means for interrupting the supply of electrical energy to said heating device at the end of its travel in one direction. 105
31. Heating apparatus having, in combination, a support for the material to be heated, a movable device disposed in proximity to said support, means for electrically heating said device, means for moving said electrically heated device slowly in one direction along said support, means for reversing the direction of movement thereof and returning said movable device rapidly in the opposite direction, and means for interrupting the supply of energy to said heating means during the return movement of said movable device. 110
32. Heating apparatus having, in combination, a support for material to be heated, a heating device disposed in proximity to said support and constructed and arranged for movement over said material but out of contact therewith, and electrical means for supplying heat to said support and said heating device. 115
33. Heating apparatus having, in combination, a support for material to be heated, a heating device disposed in proximity to said support and constructed and arranged for movement over said material but out of contact therewith, and electrical means for supplying heat to said support and said heating device. 120
34. Heating apparatus having, in combination, relatively movable electric heating devices severally disposed on the respective sides of the material to be heated, and means for moving one of said heating de- 125

32. Heating apparatus having, in combination, a support for the material to be heated, means for electrically heating said support, a movable device disposed in proximity to said support, means for electrically heating said device, means for moving said electrically heated device longitudinally of said support, and means for discontinuing the movement of said movable device 10 and interrupting the supply of energy to both of said heating means at a predetermined point in the movement thereof.
33. Heating apparatus having, in combination, a support for material to be heated, electric heating means therefor, a device disposed in proximity to said support and movable back and forth longitudinally of said support, electric heating means for said movable device, and means for intermittently supplying electrical energy to both of said heating means.
34. Heating apparatus having, in combination, a support for material to be heated, a movable heating device disposed above and in proximity to said support, power means including a feed-screw for moving said heating device longitudinally of said support, and control means for governing the direction of rotation of said feed-screw and therefore the direction of movement of said heating device.
35. Heating apparatus having, in combination, a support for the material to be heated, a movable electrical heating device disposed above and in proximity to said support, power means including a feed-screw for moving said heating device longitudinally of said support, and a manually operated reversing clutch driving mechanism for causing said heating device to be moved in either direction by said feed-screw moving means.
36. Heating apparatus having, in combination, a support for the material to be heated, a movable heating device disposed in proximity to said support, means including a feed-screw for moving said heating device longitudinally of said support, a reversing clutch driving mechanism adapted to be manually thrown into operation to cause said feed-screw moving means to move said heating device in either direction, and automatic means for disengaging said driving mechanism at a predetermined point in the movement of said heating device in either direction.
37. Heating apparatus having, in combination, a horizontal support for the material to be heated, a movable heating device disposed above and in proximity thereto, means for moving said heating device along said support and over the material disposed thereon, a horizontal work-table disposed in front of said support upon which the material is manipulated by the operator after being heated, and manually operable means disposed at the front of said work-table within easy reach of the operator throughout its length for controlling the actuation of said moving means for said heating device.
38. An electric heating apparatus having, in combination, a support for material to be heated, a movable electric heating device disposed in proximity to said support and adapted to be moved longitudinally thereof, a circuit interrupter in the supply circuit of said heating device, electro-magnetic means for closing said circuit interrupter, and automatic means dependent upon the position of said movable heating device along said support for controlling the operation of said electromagnetic closing means.
39. An electric heating apparatus having, in combination, a support for material to be heated, a movable electric heating device disposed in proximity to said support and adapted to be moved in either direction thereof, an electromagnetically operated circuit interrupter in the supply circuit of said heating device, and automatic means governed by said movable heating device at the respective limits of its movement for controlling the operation of said circuit interrupter.
40. An electric heating apparatus having, in combination, a support for material to be heated, a movable electric heating device disposed in proximity to said support and adapted to be moved in either direction thereof, an electromagnetically operated circuit interrupter in the supply circuit of said heating device, and control connections and devices in the operating circuit of said electromagnetically operated circuit interrupter for effecting the closure of said circuit interrupter when said movable heating device reaches its limit of travel in one direction and for permitting the opening of said circuit interrupter when said movable heating device reaches its limit of travel in the opposite direction.
41. An electric heating apparatus having, in combination, a support for material to be heated, a movable electric heating device disposed in proximity thereto and adapted to be moved back and forth longitudinally of said support, a circuit interrupter in the electric supply circuit of said heating device, and automatic electrical means including a plurality of control switches respectively located at the opposite limits of travel of said movable heating device and adapted to be operated by engagement therewith for governing the operation of said circuit interrupter.

ALBERT E. JOHNSON.
